UNITED STATES PATENT OFFICE.

FLORINDA GARDNER, OF SALT LAKE CITY, UTAH.

COMBINATION CLOTHES-HANGER AND IRONING-BOARD.

1,311,766.

Specification of Letters Patent. Patented July 29, 1919.

Application filed November 25, 1918. Serial No. 264,062.

To all whom it may concern:

Be it known that I, Mrs. FLORINDA GARDNER, a citizen of the United States, residing at Salt Lake City, in the county of Salt Lake and State of Utah, have invented new and useful Improvements in Combination Clothes-Hangers and Ironing-Boards, of which the following is a specification.

My invention relates to a combined ironing board and clothes hanger.

An object of my invention is to provide a light, inexpensive and convenient ironing board and hanger adapted to be carried in a wardrobe trunk.

Another object is to provide a combined ironing board and hanger which may be carried in a wardrobe trunk and which readily may be removed therefrom and laid on a table or other convenient surface for use as an ironing board.

With these and other objects in view my invention consists in the construction and arrangement of parts hereinafter described and claimed.

In the accompanying drawings which form a part of this specification,

Figure 1 is a perspective view of a wardrobe trunk in its open position illustrating a combined ironing board and hanger embodying the principles of my invention, as it is used in connection with the trunk.

Fig. 2 is a fragmentary view in side elevation of a table illustrating the use of my combined ironing board and hanger when used as an ironing board.

Fig. 3 is an enlarged sectional view on the line 3—3 of Fig. 1, showing the construction of the upper end of my combined ironing board and hanger.

The wardrobe trunk illustrated in Fig. 1 is of a common type having a drawer section 10 and a hanger section 11, the hanger section being provided with hanger rods 12 and 13 which as is usual in the construction of such trunks are hinged to the back casing and swing inwardly to approximately the middle point between the two hinges. When in their open position they extend horizontally from the back casing as shown in Fig. 1.

The combined ironing board and hanger consists of a straight board 14 of convenient width of a length somewhat less than the

height of the wardrobe trunk. Its upper and wider end has a hanger member 15 fixed in a groove formed in its upper margin by screws 16 extending through the thickness of the board and through the hanger member. The hanger member is made of relatively thin wood or metal in the usual form having a straight middle section with hooks 17 and 18 formed on its ends to engage with the hanger rods 12 and 13. A cleat 19 is fixed across the board near its upper end by screws 20. The sides of the board are cut away to form a narrowed and rounded lower end 21 across which a cleat 22 is fixed on the same side of the board as the upper cleat. The cross cleats have their bearing surfaces 23 covered with a layer 24 of felt or similar padding. The purpose of the cross cleats is to stiffen the board and to hold it away from the supporting surface so as to guard against injury from the heat of the iron, and the purpose of the padding of the cleats is to guard against scratching or marring of such surfaces as well as to increase the sliding friction between the ironing board and resting surface and thus to stabilize the ironing board.

Operation: The ironing board when employed as a hanger is used like any other hanger, the board being removed from the rods and the clothing applied in the usual way. When it is to be used as an ironing board it is removed from the wardrobe trunk and laid with the cleats down on a table or any other convenient surface, as illustrated in Fig. 2.

While I have shown the preferred form of my combined ironing board and hanger, as now known to me, it will be understood that various changes in construction and arrangement of parts may be made by those skilled in the art without departing from the spirit of my invention as claimed.

I claim:

1. A combined ironing board and clothes hanger, comprising an ironing board member, cross cleats fixed transversely on one side of said board member, and a hanger fixed to one end of said board member, said hanger having hooks adapted to engage with supporting rods such as are used in wardrobe trunks.

2. A combined ironing board and clothes

2
hanger comprising, an ironing board member having a wider end and a narrower end, padded cross cleats fixed on the same side of said ironing board member across its wider and narrower ends, and a hanger member fixed to the wider end of said ironing board member said hanger member be-

ing provided with hooks adapted to engage with supporting rods such as are used in wardrobe trunks.

10 In testimony whereof I have signed my name to this specification.

Mrs. FLORINDA GARDNER.
